(57) **CLAIM**

The ornamental design for a disc game device, as shown and described.

DESCRIPTION

FIG. 1 is a top perspective view of a disc game device of our new design;

FIG. 2 is a front view of the disc game device shown in FIG. 1 of the drawings;

FIG. 3 is a back view of the disc game device shown in FIG. 1 of the drawings;

FIG. 4 is a left side edge view of the disc game device shown in FIG. 1 of the drawings;

FIG. 5 is a right side edge view of the disc game device shown in FIG. 1 of the drawings;

FIG. 6 is a top edge view of the disc game device shown in FIG. 1 of the drawings; and,

FIG. 7 is a bottom edge view of the disc game device shown in FIG. 1 of the drawings.

The broken lines immediately adjacent the shaded surfaces depict the bounds of the claimed design, whereas all remaining broken lines depict portions of the disc game device, all of which form no part of the claimed design.

1 Claim, 7 Drawing Sheets
